UNITED STATES PATENT OFFICE.

ALVIN C. McCORD, OF CHICAGO, ILLINOIS.

DRAFT-RIGGING FOR CARS.

1,289,212.

Specification of Letters Patent. Patented Dec. 31, 1918.

Application filed December 28, 1912. Serial No. 739,039.

To all whom it may concern:

Be it known that I, ALVIN C. McCORD, a citizen of the United States, residing at Chicago, in the county of Cook and State 5 of Illinois, have invented certain new and useful Improvements in Draft-Rigging for Cars; and I do hereby declare the following to be a full, clear, and exact description of the invention, such as will enable others skilled in the art to which it appertains to 10 make and use the same.

My invention relates to draft rigging for cars and is particularly directed to an improved connection between the coupler draw 15 bar and yoke. Generally stated, the invention consists of the novel devices and combinations of devices hereinafter described and defined in the claims.

Hitherto it has been customary in draw 20 bar attachments of the standard Master Car Builders' type, to rigidly connect the yoke to the draw bar by means of rivets. These rivets have been found to be the weakest parts of the draft rigging. They are subjected to direct shearing strains and a constant twisting or bending, which makes them either come loose or shear off. Another bad feature in this rigid riveted connection between the yoke and draw bar, is 25 that in removing and renewing a coupler, it becomes necessary to lower the draw bar from its normal position and to remove all of the rivets and then to replace them with new rivets or bolts.

My invention provides an extremely simple and highly efficient flexible connection 30 between the draw bar and yoke in which the said elements are operatively connected by the application of a strong and heavy key, and the removal of this key, which is a very easy matter, permits the draw bar to be pulled out and disconnected from the yoke. This permits very quick and easy substitution of one draw bar for another.

My invention also involves other novel 40 and highly important features which will be hereinafter more fully disclosed.

In the accompanying drawings which 45 illustrate several forms of the present invention, like characters indicate like parts throughout the several views. Referring to the drawings,

Figure 1 is a view partly in plan and partly in horizontal section, some parts be-

ing broken away, illustrating one form of 55 the improved draw bar attachment;

Fig. 2 is a view of the parts shown in Fig. 1, chiefly in side elevation, but with some parts in vertical section;

Fig. 3 is a view partly in section on the 60 line $x^a x^b$ on Fig. 1, and partly in end elevation;

Figs. 4 and 5 are views corresponding, respectively, to Figs. 1 and 2, but illustrating 65 a modified construction; and

Figs. 6 and 7 are views also corresponding, respectively, to Figs. 1 and 2, but illustrating a still further modified construction.

Referring first to the construction illustrated in Figs. 1, 2 and 3, the numeral 1 indicates the draw bar of a coupler of the Master Car Builders' type. The shank of this draw bar 1 is preferably cast hollow 70 and is formed with a horizontal key-way 2 extended through its vertical walls near to 75 its rear end.

The followers 3 of the draft gear, which may be of the standard or any suitable construction, are shown as yieldingly pressed 80 against suitable adjustments or draft lugs 4, by means of a heavy coiled spring 5.

The draft yoke 6, which is preferably in the form of a crucible steel or malleable casting, embraces the followers 3 and spring 5 and normally engages with the rear 85 lower.

In this improved draft bar attachment, the yoke 6 is flexibly connected to the draw bar 1, through the intervention of a so-called 90 pocket 7. This pocket 7 is preferably bifurcated, so that it embraces the inner end of the draw bar 1, and serves as a sort of a socket to receive the same. The side flanges of this so-called pocket 7 are formed with slots or key seats 8 that align with the slots 95 or key seat 2 of the draw bar, so that the heavy connecting key 9 is adapted to be inserted through the said seats 2 and 8, to thereby couple the said draw bar to the said pocket. At the inner end portion of the 100 said pocket 7, it is provided with laterally spaced bearing lugs 10 that engage the outer follower 3 at points on opposite sides of the axial center of the draft gear, which axial center is indicated in Fig. 1 by the broken 105 line marked y .

The outer ends of the prongs of the draft yoke 6 are connected to the top and bottom

plates of the pocket 7 with freedom for both pivotal or lateral angular movements, and for longitudinal sliding movements, and this is preferably accomplished as follows:

5 The prongs of the said yoke 6 are provided with axially alined trunnions 11 having retaining flanges 12 at their extended ends, and the upper and lower plates of the pocket 7 are formed with longitudinally extended slots 13 that receive and closely fit the said trunnions 11. Also, the sides of the said slots 13 are formed with retaining grooves 14 that receive the retaining flanges 12 of said trunnions, and thus interlock the said trunnions to the said pocket and thereby positively hold the prongs of the draft yoke 6 against vertical spreading movements. The outer extremities of the slots 13 are opened so that the flanged trunnions 11 may be inserted into the said slots 13. The inner extremities of the slots 13 are rounded so that they form bearings in the trunnions and permit horizontal, angular or pivotal movements of the draw bar 1, in respect to the said yoke 6.

Obviously, the key 9 should be applied in the slots 2 and 8 of the draw bar 1 and pocket 7, respectively, after the said bracket has been coupled to the draft yoke, and after 30 the draw bar has been shoved back to position therein. When it is desired to remove the draw bar or coupler it is only necessary to remove the key 9 and then to pull the said draw bar directly out of position by 35 endwise movement on the line of the axis of the draft gear. Obviously, a new or substitute draw bar or coupler may be applied simply by inserting the same endwise into the pocket, then applying the coupling 40 key 9.

With the construction above described, it will be noted that the spring 5 normally holds the followers 3 closely pressed against the coöperating draft lugs 4 and also normally holds the outer follower 3 against the bearing lugs 10 of the coupling pocket 7. This engagement of the lugs 6 with the said follower tends to hold the draw bar 1 in a central or intermediate normal position. 45 The spring 5, of course, is thus made to serve as a yielding medium for keeping the draw bar normally centered. However, in traveling a curve the draw bar 1 may assume an angular position indicated by dotted lines 50 on Fig. 1, and in doing so, will put no lateral strains on the draft yoke 6 and no bending strains on any of the parts of the draft rigging. In fact, there are no cramping actions or unnecessary strains, what- 55 ever, put upon the elements of the draft rigging, and the flexible connection above noted permits the draw bar to assume a natural position whether traveling on a straight or on a curved track, and under 60 normal conditions when the coupler is free,

the draw bar will be held in its central position.

Under bumping strains, the draw bar 1 will force the pocket 7 and front follower 3 rearward or inward with it, but will not force the draft yoke 6 rearward, because the trunnions 11 are free to slide in the slotted trunion seats 13 of the said bracket. Under draft strains, the front outer follower, of course, remains stationary while the draw bar 1, pocket 7, yoke 6 and inner follower, all move together. This improved draft bar attachment is of extremely simple construction, is very strong and durable and, as already stated, permits the coupler draw bar to be very easily and quickly connected to or disconnected from the the draft yoke and other coöperating parts of the draft rigging.

In the modified construction illustrated in Figs. 4 and 5, the draw bar 1 and yoke 6 are shown as identically of the same construction as in Figs. 1 to 3, inclusive, and the pocket 7^a is of substantially the same construction and arrangement, being provided with the same trunion seats 13^a and retaining grooves 14^a, but having longer key seats 8^a and having its rectangular rear end portion flush with the inner end of the draw bar 1. The same coupling key 9 is here employed.

In the construction illustrated in Figs. 6 and 7, the draw bar 1 and key 9 are of the construction previously described, but the yoke 6^a in this modified arrangement is provided with longitudinal slots or trunion seats 6^b, and the so-called pocket 7^b is provided with flanged trunnions 7^c that work in the said seats 6^b.

What I claim is:

1. In a draft rigging, the combination with a yoke and a pocket, one of said parts having trunnions and the other having longitudinally extending trunion seats, the said trunnions and seats being so interlocked as to permit a sliding longitudinal movement of the former while retaining the interlocked engagement, of a draw bar seated in and connected to said pocket.

2. In a draft rigging, the combination with a yoke and a pocket, one of said parts having trunnions and the other having longitudinally extending trunion seats, said trunnions and trunion seats being so interlocked as to permit a sliding longitudinal movement of the former while retaining the interlocked engagement, said seat being open at one end for the application and removal of the trunnions thereto, of a draw bar seated in and connected to said pocket.

3. In a draft rigging, the combination with a yoke and a pocket, one of said parts having trunnions and the other having longitudinally extending trunion seats, said trunnions and seats being so interlocked as

to permit a sliding longitudinal movement of the former, while retaining the interlocked engagement.

4. In a draft rigging, the combination 5 with a yoke and a pocket, one of the said parts having headed trunnions, and the other of said parts having trunnion seats with which the said headed trunnions are interlocked with freedom for pivotal and

sliding movements longitudinally of said 10 yoke, of a draw bar seated in and connected to said pocket.

In testimony whereof I affix my signature in presence of two witnesses.

ALVIN C. McCORD.
